His Attorney.

UNITED STATES PATENT OFFICE

ELMER D. McARTHUR, OF SCHENECTADY, NEW YORK, ASSIGNOR TO GENERAL ELECTRIC COMPANY, A CORPORATION OF NEW YORK

SIGNAL TRANSMITTING MEANS

Application filed November 20, 1928, Serial No. 320,709. Renewed October 15, 1932.

My present invention relates to signal transmitting means employing electron discharge devices of the divided anode type and in which a magnetic field is produced between the anode members. A discharge device of this type is disclosed in copending application, Serial No. 285,008, filed June 13, 1928, Kinjiro Okabe entitled "Extra short wave generating device," and will be described more fully hereinafter. Particular constructions thereof are shown in my copending application, Serial No. 389,067, filed August 28, 1929, entitled "High frequency magnetron apparatus" and in application, Serial No. 398,249, Kenneth C. Dewalt, filed October 8, 1929, and entitled "Electron discharge apparatus". My invention relates more particularly to discharge devices of the type indicated when used together with circuit arrangements whereby ultra short wave oscillations are produced.

My invention has for one of its objects to provide means whereby oscillations produced by means of the type of device indicated may be efficiently modulated in accordance with desired signals.

The novel features which I believe to be characteristic of my invention are set forth with particularity in the appended claims. My invention itself, however, both as to its organization and method of operation, together with further objects and advantages thereof, may best be understood by reference to the following description taken in connection with the accompanying drawing in which Fig. 1 represents one embodiment of my invention; Fig. 2 represents a characteristic thereof, and Fig. 3 represents a modification.

Referring to the drawing I have indicated an electron discharge device of the type more fully described in my above mentioned copending application, and which comprises an evacuated vessel having disposed therein a plurality of anodes 2. These anodes are preferably curvilinear and are arranged in cylindrical formation. Extending along the axis of the cylinder formed by the anodes 2 is a heated cathode 3 which is arranged to be energized from an energy source 4. Con-

nected between the anodes 2 is an oscillatory circuit comprising inductance 5 and capacity 6. This oscillatory circuit is coupled with any suitable load circuit 7 which may, if desired, comprise a radiating system. Each of the anodes is supplied with direct current potential from a source 8 which is connected between the cathode and the mid-point of the inductance 5, although of course any other suitable connection may be employed.

The electron discharge device is provided with a direct current field winding 9 which is energized from a source of direct current potential 10 through resistances 11 and 12. This field winding produces a unidirectional magnetic flux within the discharge device and between the anodes thereof the magnetic lines of which extend parallel with the inner surface of the anodes.

If we assume that the source of potential 10 and the resistances 11 and 12 are so adjusted that a flux is produced within the discharge device of desired intensity, oscillations will be produced in the oscillatory circuit 5, 6, which oscillations are supplied to the load circuit 7. These oscillations may be of any desired frequency dependent upon the characteristic of the oscillatory circuit. It has been found in a particular case in which inductance 5 consisted only of the inductance of the leads which extend from the anodes through the walls of the vessel and which were then connected together by a copper bar, and the capacity 6 consisted only of the capacity between the anodes and connected leads, which anodes were of about a centimeter in diameter and of somewhat greater length, that oscillations were produced having a wave length of but a few centimeters. It has also been found that by properly proportioning the circuits these oscillations may be made of very low frequency. Frequencies as low as sixty cycles have been produced.

The intensity of the oscillations which are produced in the circuit 5, 6 varies with respect to the strength of the current in the field circuit in the manner shown by the curve 13 of Fig. 2 in which the intensity of oscillating current is plotted as ordinates and

that of the field current is plotted as abscissa. It will be seen that as the field current increases and, hence, as the intensity of the magnetic flux within the discharge device 5 increases, the intensity of the oscillatory current also increases in an approximately linear relation until a critical point is reached as represented by the top of the curve 13, at which point oscillations entirely cease. 10 Thus, for example, if the device is to be utilized as a telegraphic transmitter, the resistance 11 may be so adjusted that the current flowing in the field circuit is such that the oscillations produced have desired intensity 15 and resistance 12 will be of such a value that when short circuited as by means of a key 14, the field current will increase to a point such that no oscillations are produced. Thus by 20 opening and closing the key 14, the production of oscillations may be interrupted in accordance with desired signals. Keying may also be effected, of course, by varying the field current from zero, or some low value, to a higher value at which oscillations of 25 desired intensity are produced.

For telephonic communication the intensity of the field current should preferably be adjusted at some value as, for example, at a 30 value represented by the point B on the curve 13, such that the intensity of the oscillations produced is about half of the maximum value. The resistance across the terminals of resistance 12 may then be varied in accordance with voice waves, as by means of a microphone connected in shunt therewith, thereby 35 to increase and diminish the intensity of the oscillations in the circuit 5, 6 in the relation expressed by that portion of the curve 13 lying between limits represented, for example, by points A and C. In this way voice 40 modulation of the oscillations produced may be conveniently and efficiently effected.

In Fig. 3 I have shown a modification of 45 my invention in which the electron discharge device comprises a plurality of pairs of anodes 2, 2', these pairs of anodes having connected therebetween oscillatory circuits 15, 15' respectively. In this case the load circuit 7 is associated with all of the oscillatory 50 circuits 15, 15' and is adapted to be supplied with high frequency current therefrom. The oscillatory circuits 15 and 15' are tuned 55 preferably at the same frequency, and each of them cooperate with the pair of anodes to which they are connected to produce oscillations in the manner mentioned in connection 60 with Fig. 1. The oscillations in all of these circuits may be synchronously modulated and, hence, the oscillations in the load circuit 7 may be modulated in the manner described 65 in connection with Fig. 1, although in Fig. 3 I have represented a key as replaced by a microphone 16. It will be understood, of course, that either of these devices

The number of pairs of anodes employed in the modification shown in Fig. 3 may of course be increased as desired, each pair being arranged symmetrically with respect to the cathode and all of the anodes being arranged preferably in cylindrical formation about the cathode. 70

One of the important advantages of the system described resides in the fact that the high frequency power output from a transmitter employing an electron discharge device of the type indicated can be increased by increasing the radial dimensions of the device without encountering the limitation encountered in the use of three-element electron discharge devices of the usual type resulting from internal capacity between the electrodes. In increasing the radial dimensions of the discharge device employed it has been found that so long as the ratio between the radius of the anode cylinder and the width of the slit D between adjacent anodes is kept constant the limit of frequency at which the device will operate will not be changed. That is, the internal capacity will 80 remain constant. 85

While I have shown particular embodiments of my invention, it will of course be understood that I do not wish to be limited thereto since many modifications, both in the circuit arrangement and in the instrumentalities employed, may be made without departing from the spirit and scope of my invention as set forth in the appended claims. 90

What I claim as new and desire to secure by Letters Patent of the United States, is:

1. The combination, in a high frequency transmitter, of an electron discharge device, having a cathode and a plurality of anodes, 105 said anodes being symmetrically arranged with respect to the cathode and adjacent thereto, an oscillatory circuit connected between said anodes, means for producing a unidirectional magnetic field between said anodes, said magnetic field being independent of current in said oscillating circuit, and means for varying said magnetic field in accordance with the signal to be transmitted thereby to vary the intensity of the oscillations produced in said oscillatory circuit. 110

2. The combination, in a high frequency transmitter, of an electron discharge device having a cathode and a plurality of anodes, 115 said anodes being symmetrically arranged with respect to the cathode and adjacent thereto, an oscillatory circuit comprising the inherent capacity between said anodes, and an inductance connected between said anodes, a field circuit for producing a magnetic field 120 between said anodes, circuit connections whereby oscillations are excited in said oscillatory circuit, the intensity of the oscillations being variable dependently upon the intensity of the magnetic field and said os- 125

cillations ceasing when the intensity of the magnetic field reaches a predetermined maximum value, and means for alternately adjusting the intensity of the magnetic field 5 above and below said maximum value in accordance with desired signals.

3. The combination, in a high frequency generator, of an electron discharge device having a cathode and a plurality of anodes, 10 said anodes being arranged in pairs, the anodes of each pair being disposed on opposite sides of said cathode, a plurality of oscillatory circuits, each of said oscillatory circuits including an inductance connected between a pair of said anodes and means for producing a magnetic field between each pair of said anodes whereby oscillations are excited in all of said oscillatory circuits. 15

4. The combination, in a high frequency generator, of an electron discharge device having a cathode and a plurality of anodes, said anodes being arranged in pairs, the anodes of each pair being disposed symmetrically with respect to said cathode, a plurality 25 of oscillatory circuits, each of said oscillatory circuits including an inductance connected between a pair of said anodes, means for producing a magnetic field between each pair of said anodes whereby oscillations are 30 excited in all of said oscillatory circuits, and means for modulating the oscillations produced in all of said oscillatory circuits.

5. The combination, in a high frequency transmitter, of an electron discharge device, 35 having a plurality of pairs of anodes arranged in cylindrical formation, an electron emitting cathode extending along the axis of the cylinder formed by said anodes and each of said pairs of anodes being arranged 40 on opposite sides of said cathode, a plurality of oscillatory circuits, each of said oscillatory circuits including a pair of anodes, means for producing a magnetic field extending parallel with the inner surface of said 45 anodes and between each pair of anodes whereby oscillations are produced in said oscillatory circuits and means for modulating the oscillations produced.

6. The combination, in a high frequency generator, of an electron discharge device having a cathode and a plurality of anodes, said anodes being arranged in pairs, the anodes of each pair being disposed on opposite sides of said cathode, a plurality of oscillatory circuits, each of said oscillatory circuits including an inductance connected between a pair of said anodes, means for producing a magnetic field between each pair 55 of said anodes whereby oscillations are excited in all of said oscillatory circuits, said means including a normally energized field circuit, a load circuit supplied with high frequency oscillations from each of said oscillatory circuits, and means for superimposing 60 signal current upon the current normally 35

flowing in the field circuit thereby to modulate the oscillations supplied to said load circuit.

In witness whereof, I have hereunto set my hand this 19th day of November, 1928. 70
ELMER D. McARTHUR.
